United States Patent Office

Des. 210,658

Patented Apr. 2, 1968

210,658

TRACTOR CAB

Edward J. Lazzeroni, Racine, Wis., assignor to J. I. Case Company, Racine, Wis., a corporation of Wisconsin

Filed June 29, 1967, Ser. No. 7,637

Term of patent 14 years

(Cl. D14—27)

FIG. 1 is a front perspective view of my design for a tractor cab.

FIG. 2 is a rear elevational view of FIG. 1.

FIG. 3 is a top plan view of FIG. 1.

I claim:

The ornamental design for a tractor cab, substantially as shown.
